CLAIM

The ornamental design for a Christmas tree stand as shown and described.

DESCRIPTION

FIG. 1 is a front perspective view of a Christmas tree stand showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings represent portions of the Christmas tree stand and form no part of the claimed design.
